(57) **CLAIM**

The ornamental design for a multi purpose hand operated office utensil, as shown and described.

DESCRIPTION

FIG. 1 is a top perspective view of a multi-purpose hand operated office utensil showing my new design;

FIG. 2 is a bottom perspective view of FIG. 1;

FIG. 3 is a left side elevational view of FIG. 1;

FIG. 4 is a right side elevational view of FIG. 1;

FIG. 5 is a top plan view of FIG. 1;

FIG. 6 is a bottom plan view of FIG. 1;

FIG. 7 is a rear elevational view of FIG. 1;

FIG. 8 is a front elevational view of FIG. 1;

FIG. 9 is a second top perspective view of my design of FIG. 1;

FIG. 10 is a bottom perspective view of FIG. 9;

FIG. 11 is a left side elevational view of FIG. 9;

FIG. 12 is a right side elevational view of FIG. 9;

FIG. 13 is a top plan view of FIG. 9;

FIG. 14 is a bottom plan view of FIG. 9;

FIG. 15 is a rear elevational view of FIG. 9; and,

FIG. 16 is a front elevational view of FIG. 9.

The variety of structural elements depicted by means of broken lines in FIGS. 1-16 have been shown for environmental purposes only and form no part of the claimed design.

1 Claim, 6 Drawing Sheets
